UNITED STATES PATENT OFFICE

2,567,231

HOIST WINCH

Homer B. Nelson, Vandalia, Ohio

Application February 21, 1950, Serial No. 145,517

2 Claims. (Cl. 254—167)

(Granted under the act of March 3, 1883, as
amended April 30, 1928; 370 O. G. 757)

1

The invention described herein may be manufactured and used by or for the United States Government for governmental purposes without payment to me of any royalty thereon.

This invention relates to a hoist winch and is particularly adapted for loading bundles, boxes or similar packages into an aircraft.

The embodiment of the invention herein shown and described is sufficiently light in weight to be carried about by one man, and, at the upper end, has clamping means whereby it may be removably attached to the conventional rail which extends longitudinally midway of the width and close to the ceiling of the fuselage. The lower end of the hoist, when in operative position is about as high from the floor of the fuselage as half the operator's height, and carries the manually operable mechanism for clamping the device to the rail, for raising or lowering the load, or for locking it in the raised or any intermediate position.

An object of the invention is to provide a device of this character which is extremely light in weight, simple and inexpensive in construction and effective in operation.

I attain this and other objects and advantages in the mechanism hereinafter shown and described with reference to drawings wherein:

Fig. 1 is a side elevation of a hoist showing the mechanism for clamping it in the operative position.

Fig. 2 is a portion of a rear elevation taken to an enlarged scale, part being in section, showing the gearing of the cable winding mechanism.

Figs. 3 and 4 are top and side elevations respectively of the crank used for raising the load, the view being drawn to an enlarged scale.

Fig. 5 is a partial section drawn to an enlarged scale through the load retaining mechanism the view being taken at 5—5 of Fig. 1.

Fig. 6 is an enlarged fragmentary section taken at 6—6 of Fig. 2 showing a detail of the cable winding mechanism.

Fig. 7 is an enlarged section taken at 7—7 of Fig. 1 showing the locking lever used for locking the rail clamping mechanism.

Fig. 8 is an enlarged section taken at 8—8 of Fig. 1 showing a detail of the clamping mechanism operating rod and its bearing.

Like reference characters refer to like parts throughout the several views.

In the apparatus herein shown as an embodiment of my invention, an elongated tubular member 10 is provided at the upper end with a bracket 12 and at the lower end with a housing

14. The bracket 12 and housing 14 are each provided with a cylindrical end portion 16 which is preferably closely fitted to the inside of the tubular member 10 and fixed therein by transverse bolts 18. The bracket 12 rotatably supports the sheaves 20 and, at the extreme end, is provided with an integral hinge ear 22 which rockably supports a rail clamping lever 24. Above the hinge ear 22 the bracket 12 carries a stationary clamping pad 26 which may be engaged as shown in phantom by a pad 28 which is hinged at 30, thereby to adjustably grip the rail of the airplane fuselage as indicated in the drawing.

5 Hinged at 32 to the lower end of the clamping lever 24 is a clamp operating arm 34, the lower end of which is hinged at 36 to the upper end of the clamp operating rod 38. Bronze guide blocks 40 (see Fig. 8) for the operating rod 38 are adjustably held by screws 42 in the band 44 thereby to permit an aligning of the blocks to minimize friction of the rod in the blocks. Bands 44 are fixed against longitudinal movement on the tubular member 10 by the screws 46.

10 The lower end of the operating rod 38 is secured by a pin 48 (see Fig. 2) to the hub of the band 50. The band 50 is bifurcated to admit the clamping handle 52. A clamping block 54 (see Fig. 7) on one side is concaved to fit the tubular member 10 and on the other side is grooved to fit an eccentric cam 56 formed on the end of the handle 52, whereby turning of the handle about the axis of the operating rod 38 locks the band 50 against axial movement on the tubular member 10. The band 50 is not otherwise fastened against longitudinal movement on the tubular member 10, whereby when the handle 52 is in the central position shown in Fig. 7, it may be used to slide the band 50 axially on the tubular member 10 thereby to operate the rod 38, arm 34 and lever 24 to clamp the device onto the rail.

15

The housing 14 covers the toothed side of the gearing 58 through which the drum 60 is rotated by the crank 62 (see Figs. 2, 3 and 4). The gearing 58 comprises an internal gear 64, the teeth of which consist of a series of circumferentially spaced round pins 66 nonrotatably supported by and between two axially spaced flanges 68 and 70. The drum 60 may be integral with the internal gear 64 as shown or separately made and attached thereto as desired.

A short shaft 72 is rotatable in a bearing sleeve 74 which is press fitted into a hub of the housing 10, and at the inner end has securely fixed thereon 55 a pinion 76 the teeth of which are permanently

in driving engagement with the pins 66 of the gear 64. A spool-like crank connecting member 77 which carries an annular groove 79, cross drilled at four places as at 81 for engagement of the crank plunger as hereinafter described, is fastened to the shaft 72 by a pin 83.

A second shaft 78 is preferably nonrotatably fixed in a hub of the housing 10 and runingly fitted into a bearing sleeve 80 which is press fitted into a hub of the internal gear 64. A nut 82 prevents axial movement of the gear 64 off the shaft. Shaft 78 provides rotative bearing for the internal gear 64 and the drum 60.

In order to hold the load suspended at any desired height, a ratchet-and-pawl mechanism 84 is provided (see Figs. 1 and 5). Mechanism 84 comprises a shaft 86 having rotative bearing in a hub of the housing 10, a pawl 88 fast on the shaft 86 inside the housing, and a thumb disengaging latch 90 fast on the shaft 86 outside the housing by a pin 92. The swingable end of the pawl 88 is fashioned to fit between adjacent pins 66 of the internal gear 64, whereby the same pins 66 serve as ratchet teeth as well as gear teeth. A torsion spring 94 normally holds the pawl 88 engaged with the pins 66.

A cable 96 has one end attached to the drum 60 by a fastener 98 then is passed over the sheaves 20 down to the link 100 which holds the hook 102.

The crank 62 comprises a casting 104, bored at 106 to receive the crank engaging member 77 on the shaft 72 (see Fig. 2). Guide lugs 108 and 110 are provided in the casting 104 for the crank engaging plunger 112 which is biased by the spring 114 for engagement in the openings 81 in the crank connecting member 77.

Held on the tail end of the plunger 112 by a nut 116 is a hub 118 which has a crank lockout handle 120 extending therefrom, and formed in one side of the casting 104 is a T slot 122 through which the crank lockout handle 120 extends. If the lockout handle 120 is turned about the axis of the plunger 112 clockwise (viewed from right to left) as far as it will go, the spring 114 will seat the plunger 112 in the groove 79 (see Fig. 2) and if and when the plunger 112 becomes aligned with one of the holes 81 by relative rotation between the crank 62 and the crank connecting member 77, the spring 114 will force the plunger into cranking position.

In the position shown in Fig. 4, the plunger 112 extends into the annular groove 79 but not into one of the holes 81. In this position the crank connecting member 77 may rotate freely in the bore 106 of the crank 62 without turning the crank. A shallow indentation 124 in the side of the T slot 122 maintains the lockout handle 120 in the position shown. In order to remove the crank 62 completely from the connecting member 77 the lockout handle 120 must be drawn leftward in the upper part of the T as far as it will go. A rotatable handle 126 on a stud 128 which is fastened in the free end of the crank casting 104 by a pin 130 provides for manual rotation of the crank.

In order to hold the cable 96 closely to the drum 60 to facilitate level winding, a spring tension device is provided which is supported on a stud 132 in the side of the housing 14. The spring 134 of this tension device is made of a strip of relatively thin sheet spring steel formed as at 136 around the underside of the stud 132 the ends extending upwardly in V fashion as at

138, Fig. 6, the extreme ends being curled as at 140 to support the shafts 142 of the small rollers 144. The underside of the V is transversely slit as at 146, Fig. 2, and formed upward as at 148 whereby the portion 148 of the bottom of the V lies on the upper side of the stud 132 and the portions 136 lie on the underside of the stud 132 and the rollers 144 are yieldably held in the position shown which allows space between the rollers 144 and the drum 60 for the cable 96.

In operation, the lockout handle 120 (see Figs. 3 and 4) is raised to the top of the T slot then drawn leftward until the plunger 112 is completely withdrawn from the bore 106 in which position the bore of the crank 62 may be pushed over the connecting member 77 and the lockout handle released so that the spring 114 may enter the plunger 112 into one of the four holes 81 when the plunger becomes aligned with either of them. A handle 150 (see Fig. 1) is provided for steadyng the hoist when cranking is being effected. In lowering a load, the lockout handle 120 may be released to the position shown in Figs. 3 and 4 whereby the drum 60, gearing 58 and connecting member 77 may rotate freely without turning the crank 62.

To clamp the apparatus in position on the aircraft rail, the operator lays the pad 26 against the forward face of the rail, sees that the handle 52 is in the straight-out position, raises the handle 52 to swing the lever 24 to the clamping position shown in phantom in Fig. 1, then turns the handle 52 about the axis of the rod 38 to lock the parts in the operative position.

When the apparatus is clamped in the operative position shown in Fig. 1, the tubular member 10 assumes an angle of approximately thirty degrees with the vertical, which together with the fact that the housing 14, crank 62 and handle 150 are then about half an average man's height from the floor upon which the operator stands, puts the operator out of the path of the bundles or boxes being lifted. This is one of the valuable features of the invention.

Having described my invention, I claim:

1. A winch hoist for storing bundles in an aircraft, which comprises, in combination, a bracket containing a clamping mechanism at the upper end which is adapted for gripping the conventional rail of an aircraft fuselage, a housing containing a cranking mechanism at the lower end and a cable drum adapted to be rotated thereby, a tubular column extending from the bracket of the clamping mechanism downward at an angle with the vertical between twenty-five and thirty-five degrees to the housing of the cranking mechanism, the cranking mechanism being substantially as high from the floor of the fuselage as half the height of an average person, a clamp operating arm hinged to the clamping mechanism, a clamp operating rod alongside said tubular column operatively hinged to the clamp operating arm, guide means for said clamp operating rod carried by said column for enabling longitudinal movement of said clamp operating rod, a clamp operating and locking handle fast on the lower end of said clamp operating rod movable upward for raising said clamp operating rod for closing said clamping mechanism and rotatable for locking said clamp operating rod in the raised position, a pin gear rotatable within said housing rotatably connected to said drum, a pinion in constant mesh with said pin gear, a crank removably secured to said pinion for rota-

tion thereof, a handle extending from said housing for steadyng the device while cranking, a pawl spring-biased to engage the pins of said gear to compose a ratchet of said gear, manual means for tripping said ratchet, friction means to tauten a cable as it is being wound on said drum, and a lifting hook at the free end of said cable.

2. A winch hoist for storing bundles in the fuselage of a carrier, which comprises, in combination, a bracket, a clamping mechanism at the upper end of said bracket, said clamping mechanism being adapted for gripping an elevated rail within said carrier, a housing at the lower end of the hoist, a cranking mechanism and a cable drum supported by said housing, said drum being adapted to be rotated by said cranking mechanism, a tubular column extending from the bracket of the clamping mechanism downward at an angle of approximately thirty degrees with the vertical to the housing of the cranking mechanism, the cranking mechanism being substantially as high from the floor of the carrier as half the height of an average person, a clamp operating arm operatively connected to the clamping mechanism, a clamp operating rod alongside said tubular column operatively connected to the clamp operating arm, guide means carried by said column for enabling longitudinal movement of said clamp operating rod, a clamp operating

5
